FLASH ROASTING

Horace Freeman, Montreal, Quebec, Canada, assignor to Nichols Engineering & Research Corporation of Canada, Limited, Montreal, Quebec, Canada, a corporation of Canada

Application January 8, 1935, Serial No. 817

6 Claims. (Cl. 266—20)

This invention relates to roasting furnaces and more particularly to furnaces for flash roasting relatively finely divided ore while in suspension within the roasting chamber of the furnace. Features of this invention have been found to be particularly adaptable to the roasting of sulphide ores such as pyrite and pyrrhotite for the production of sulphur dioxide gas and iron oxide products. However, the invention is adaptable to the roasting of various other types of ores.

This invention is directed to improvements upon and modifications of the roasting apparatus and methods referred to in my United States Patent No. 1,812,397 and in my copending applications Ser. No. 433,471, filed March 5, 1930, Ser. No. 601,138, filed March 25, 1932 and Ser. No. 633,439, filed September 16, 1932, reference to which is hereby made for a more complete description of such portions of the furnace and auxiliary apparatus and methods as may not be fully explained or repeated hereinafter.

The invention is especially directed to features of construction and methods for introducing the finely divided ore into the flash roasting chambers of furnaces of the types described in the above mentioned patent and applications, in such manner that the ore will be properly distributed and maintained in suspension to enable the methods referred to in said patent and applications to be carried out with a high degree of efficiency and economy.

The invention consists of such novel features, arrangements, combinations of parts and methods as may be shown and described in connection with the arrangements of apparatus herein disclosed, by way of example only and illustrative of a preferred embodiment.

Various further specific objects, features and advantages will more clearly appear from the detailed description given below, taken in connection with the accompanying drawings which form a part of this specification.

In the drawings, Fig. 1 is a vertical sectional view taken substantially along the vertical axis of a furnace construction embodying the invention;

Fig. 2 is a vertical sectional view of a nozzle assembly for introducing the ore into the top of the furnace of Fig. 1;

Fig. 3 is a top or plan view of the assembly of Fig. 2;

Fig. 4 is a detailed view partly in section of the inner member or "turbine" of the assembly of Fig. 2; and

Fig. 5 illustrates in perspective the said "turbine" member.

The furnace as shown in Fig. 1 may comprise a relatively tall and substantially cylindrical roasting chamber having side walls as at 10 of a suitable refractory material, a somewhat arched roof 11 of similar material and a converging relatively cone shaped lower portion 12 terminating at the bottom with a cinder outlet as at 13.

The relatively finely divided ore to be roasted may be introduced with a stream of air or other oxidizing fluid, through the nozzle assembly as at 14, preferably located substantially at the middle of the top or roof of the furnace. With the nozzle assembly constructed in the manner herein-after described, the ore particles are carried into the roasting chamber at a relatively low velocity and are distributed in the chamber with considerable turbulence while being met by an additional supply of uprising air or other oxidizing fluid introduced through the cinder outlet 13. The gaseous products of combustion are preferably withdrawn from the furnace through one, two or more gas outlets as at 15, located in the walls of the upper portion of the chamber. The gaseous products of combustion are preferably withdrawn by a suitable suction fan capable of drawing into the roasting chamber through the cinder outlet 13, a sufficient supply of uprising air to maintain the falling particles in suspension for a short period and to provide an oxidizing medium sufficient when taken with that introduced through the nozzle, to cause the ore to be roasted to the desired degree.

The construction and operation of the nozzle assembly 14 and its associated parts will now be described. As above stated, this assembly is preferably located either at or adjacent the middle of the roof of the furnace in order that the falling shower of ore particles will be maintained in a more or less concentric relationship to the walls of the furnace, thus substantially avoiding contact of the falling particles with the furnace walls, since under some circumstances contact of the particles while being roasted, with the walls, may result in troublesome accumulations on the walls. The nozzle assembly may preferably be mounted in a cylindrical nozzle protecting member as at 16, supported by suitable framework as at 17 and extending down through the roof 11 of the furnace and terminating substantially flush with the inner surface of the roof. A cylindrical nozzle member 18 may be removably mounted within this protective member. If desired, the members 16 and 18 may be of such diameters as shown

that a small annular space is provided between the inner wall of the member 16 and the outer wall of the member 18. The member 18 when in position, may be suspended from the top of the member 16, as for example by a suitable flange 19 formed on the outer surface of the member 18. The top of the member 18 may also be provided with a suitable flange as at 20, designed to be bolted to the conduit for conveying the ore and oxidizing medium to the furnace. The bottom edges or the outlet portions of the member 18 may preferably be somewhat constricted as at 21 for aiding in the control of the falling stream of ore and oxidizing medium.

15 A "turbine" member 22 may be removably mounted within and adjacent the lower end of the nozzle member 18. This "turbine" member which is illustrated in detail in Figs. 3-5, may comprise a central portion as at 23, preferably 20 substantially cylindrical, forming a central vertical opening for directing a part of the ore stream downwardly substantially axially of the furnace. This portion may be surrounded by a plurality of outer openings formed by a plurality 25 of blades or vanes as at 24, which may be conveniently cast integrally with the portion 23 and extend in a generally radial direction outwardly from the outer surface of the portion 23. This "turbine" member may be held in place within 30 the nozzle member 18 as by one or more lugs or threaded pins as at 25 extending through the walls of the member 18 and engaging lugs as at 26 formed on the vanes 24. The various blades or vanes 24 are preferably made alike and the 35 active surfaces thereof start at the top in a substantially vertical position, these surfaces being gradually curved so that at the bottom edges of the blades, the surface extends to a substantially acute angle in respect to a vertical plane. Although the curvature of these blades may be varied somewhat, depending upon the proportions 40 of the furnace, the kind of ore treated and the pressure of the ore and oxidizing medium as introduced through the nozzle, in the preferred example illustrated, the horizontal elements of 45 the active surfaces of these blades may comprise substantially straight and radial lines, so arranged that the surfaces progress from a vertical position at the top edge of the blades gradually to an acute angle to the vertical at the bottom edges of the blades. As indicated in Fig. 2, the outer ends of the blades do not need to extend 50 to the walls of the nozzle throughout their height.

In operation the oxidizing medium and finely 55 divided ore, preferably of a substantially uniform mixture, may be blown through a suitable conduit connected to the top of the nozzle whereby the mixture passes downwardly through the nozzle under a relatively low pressure, for example, positive static pressure of from $\frac{1}{2}$ " to 4" w. g. Under normal operating conditions with a furnace and with a nozzle of the proportions indicated in the drawings for the roasting of pyrite, I have found that pressures of from $\frac{1}{2}$ " to 1" 60 w. g. give most satisfactory results. However, if a portion of the outlet gases are recirculated back into the nozzle intake for the purpose of improving temperature control conditions within the furnace, it may be desirable to increase the 65 pressures somewhat as compared with those last above stated. The pressure should preferably be so adjusted that it is sufficiently high to insure proper distribution of the ore in the furnace in the manner hereinafter described, and yet not 70 too high lest the ore particles be driven into the

combustion chamber too rapidly to permit time for complete combustion. Also, if the pressure is too high, ore particles may impinge upon the furnace walls, which may lead to the difficulty above mentioned, i. e., the formation of troublesome accumulations on the walls. The pressure should also be sufficiently low so that gas is not driven out through the cinder opening at the bottom of the furnace.

In passing through the nozzle member 18, a substantial part of the incoming ore and oxidizing medium pass down through the central opening in the cylindrical portion 23. This stream of the material acts as an axis, giving direction to the ore and gases. The remainder of the ore and oxidizing medium pass through the outer openings between the blades 24, much of it impinging against the curved surfaces of the blades, so that these outer streams are given a rotational movement providing jets which intersect and cut into and through the central jet. This results in a substantial turbulence of the ore and oxidizing medium, scattering the same as a downwardly expanding cone, which however does not extend to its maximum dimensions until at 25 a point substantially below the outlets 15. In this way the carrying over of any substantial amounts of dust or ore particles through the outlets 15 is avoided. To this same end, the suction on the gases of combustion passing out of the outlets 15 is kept relatively low. Also, this cone of ore particles and oxidizing medium even at its portions of maximum diameter, does not extend into substantial contact with the furnace walls.

With the nozzle parts of the relative proportions substantially as shown in the drawings and with the nozzle member 18 having an inside diameter of approximately 1 ft., I have found that a furnace chamber having an inside diameter of about 11 ft. and with vertical dimensions in the proportion shown in Fig. 1, gives excellent results. However, with such a nozzle, the furnace diameter may well be varied from in the neighborhood of 10 ft. to 16 ft. depending upon the character of the ore being treated, and various other conditions.

The height of the "turbine" member 22 within the nozzle member 18 may be suitably adjusted by trial until the best roasting conditions are secured, and this member may then be fixed in the desired position by properly locating the threaded pins 25 in the nozzle walls. In the event it is desired to alter the roasting conditions or treat various different ores, the "turbine" member 22 may readily be removed through the top of the nozzle and replaced by another "turbine" member having an altered blade curvature or having a central opening of a different size if desired, to meet special conditions, and whereby the ore will be uniformly distributed, yet the falling cone of ore will be kept substantially within the limits above described.

The manner in which the falling suspension of ore is met by the uprising supply of oxidizing medium from the cinder outlet 13, with the gases of combustion going out the outlets at the top, is more fully set forth in the above mentioned co-pending applications.

I find that the outlet of the nozzle assembly should preferably just project through the roof of the furnace, whereas if it projects down into the furnace to any great extent, interfering crusts may accumulate on its outside walls, ultimately obstructing the flow at the outlet of

the nozzle and interfering with its proper action.

While the invention has been described in detail with respect to a preferred and satisfactory example, it will be understood by those skilled in the art after understanding the invention as above described, that various changes and modifications may be made without departing from the spirit and scope of the invention, 10 and it is intended therefore in the appended claims to cover all such changes and modifications.

What is claimed as new and is desired to be secured by Letters Patent is:

15 1. In a furnace for flash roasting finely divided ore particles in suspension, a roasting chamber, a nozzle at the midportion of the roof of said chamber for introducing the ore particles with a stream of gaseous medium, an opening being provided within said nozzle for discharging the central portion of said stream in a vertically downward direction, said opening being surrounded by an annular space providing additional ore discharge openings within said nozzle, and a 25 plurality of curved vanes within said annular space for creating a turbulent condition in the ore and gaseous medium passing through said annular space.

2. In a furnace for flash roasting finely divided ore particles in suspension, a roasting chamber, a nozzle at the upper part of said chamber for introducing the ore particles with a stream of gaseous medium, means fixed within said nozzle adjacent its outlet for controlling a spray of 30 the ore particles from the nozzle, said means having a central portion with an opening for discharging a central jet of the particles substantially axially of the spray, and a plurality of vanes extending from said central portion for 35 engaging ore particles forming the part of the spray surrounding said central jet, said vanes having curved surfaces for creating a turbulent condition in said surrounding portions of the stream, and said turbulent condition extending 40 into said central jet whereby the ore is distributed as a downwardly expanding conical spray.

3. In a furnace for flash roasting finely divided ore particles in suspension, a roasting chamber, a nozzle at the midportion of the roof of said chamber for introducing the ore particles with a stream of gaseous medium, means within 45 said nozzle and adjacent its outlet for controlling the form of the spray of ore emanating there-

from, said means having a central opening for discharging the middle portion of said spray in a vertically downward direction, and a plurality of vanes surrounding said central opening for engaging the ore forming outer parts of said spray 5 and for imparting to said outer parts a turbulent rotational condition whereby the ore is discharged from the nozzle as a downwardly expanding conical spray.

4. A process of roasting ores which comprises 10 introducing the same in finely divided form into the top of a roasting chamber with a stream of air or other oxidizing medium under a relatively low pressure, and controlling said ore particles as a falling spray consisting of a vertically downwardly directed central jet surrounded by a turbulent annular rotating downwardly expanding jet intersecting said central jet and distributing the ore as a falling spray substantially confined within a downwardly expanding conical 15 space.

5. In a furnace for flash roasting finely divided ore particles in suspension, a roasting chamber, a nozzle at the midportion of the roof of said chamber for introducing the ore particles with a stream of gaseous medium, an opening being provided within said nozzle for discharging the central portion of said stream in a vertically downward direction, said opening being surrounded by an annular space providing additional ore discharge openings within said nozzle, a plurality of curved vanes within said annular space for creating a turbulent condition in the ore and gaseous medium passing through said annular space, means for introducing at the lower part of said chamber an uprising supply of gaseous medium, and outlet means at the upper part of the chamber for the gases of combustion.

6. A process of roasting ores which comprises introducing the same in finely divided form into the top of a roasting chamber with a stream of air or other oxidizing medium under a relatively low pressure, controlling said ore particles as a falling spray consisting of a vertically downwardly directed central jet surrounded by a turbulent annular rotating downwardly expanding jet intersecting said central jet and distributing the ore as a falling spray substantially confined within a downwardly expanding conical space, introducing an uprising stream of gaseous 50 medium in the chamber, and withdrawing the gaseous products of combustion from the upper portion of the chamber.

HORACE FREEMAN.
